(57) **CLAIM**

The ornamental design for the feeding bottle, as shown and described.

DESCRIPTION

FIG. 1 is an upper perspective view of the feeding bottle showing my new design;

FIG. 2 is a lower perspective view thereof;

FIG. 3 is a top plan view thereof;

FIG. 4 is a bottom plan view thereof;

FIG. 5 is a side elevation view thereof, an opposite side view being identical; and,

FIG. 6 is a front elevation view thereof, a rear view being identical.

The portions of the disclosure shown in broken lines form no part of the claimed design.
